UNITED STATES PATENT OFFICE.

LUTHER SCOTT, OF GARDEN GROVE, IOWA, ASSIGNEE OF ONE-HALF TO MAY CONNER,
OF GARDEN GROVE, IOWA.

CIRCLE-SWING.

1,225,506.

Specification of Letters Patent.

Patented May 8, 1917.

Application filed October 23, 1916. Serial No. 127,261.

To all whom it may concern:

Be it known that I, LUTHER SCOTT, a citizen of the United States, and resident of Garden Grove, in the county of Decatur and 5 State of Iowa, have invented a certain new and useful Circle-Swing, of which the following is a specification.

The object of my invention is to provide a circle swing of simple, durable and inexpensive construction.

A further object is to provide a circle swing having a support and a plurality of seats adapted to rotate around the support, the parts being so constructed and arranged 15 that the seats may be raised or lowered with relation to the support.

A further object is to provide such a device having means whereby a child sitting in one of the seats may cause the swing seats to 20 rotate.

My invention consists in the construction, arrangement and combination of the various parts of the device, whereby the objects contemplated are attained, as hereinafter more 25 fully set forth, pointed out in my claim, and illustrated in the accompanying drawings, in which:

Figure 1 shows a top or plan view of a circle swing embodying my invention.

Fig. 2 is a horizontal sectional view taken on the line 2—2 of Fig. 3.

Fig. 3 shows a vertical, sectional view, taken on the line 3—3 of Fig. 1, and

Fig. 4 shows a side elevation of my improved circle swing.

In the accompanying drawings I have used the reference numeral 10 to indicate generally a base or standard having in its central portion a socket 11 in which is supported an upright 12 preferably in the form of a hollow tube having on its upper end a cap 13.

Slidably mounted on the upright 12 is a collar or block 14, which is adjustably secured to the upright 12 in a variety of positions by means of a set screw 15. The upper part of the collar 14 is beveled at 16 to form a portion of a ball race.

Above the collar 14 on the upright 12 and 50 spaced therefrom, is a sleeve 17. On the lower part of the sleeve 17 is a ball race member 18, and between the ball race members 18 and 16 are balls 19.

Mounted on the sleeve 17 above the ball 55 race member 18 is a collar 21 having extend-

ing outwardly therefrom a plurality of flanges or bars 22. Bolted or otherwise detachably mounted on the flanges 22 are the backs of seats 23.

Resting above the sleeve 17 is a ball race 60 24 in which are balls 24^a, above which ball race is a cover cap 25 having a downwardly extending annular flange 26 extending downwardly over the upper end of the sleeve 27^a. The cover cap 25 and flange 26 form a 65 collar, and extending outwardly from the flange 26 are flanges or bars 27 similar to the flanges 22 and similarly secured to the backs of the seats 23.

Rotatably mounted on the support 12 and 70 resting upon the cover cap 25 is a lever 28. At the inner end of the lever 28 is a yoke formed of an upward extension 29 and an arm 30 extending from the extension 29 to the upright 12, and rotatably mounted on 75 said upright in a position spaced from the body portion of the lever 28 which is mounted on the upright. Pivotedly mounted between the body portion of the lever and the arm 30 is a pawl 31.

Mounted on the upright 12 between the arm 30 and the body of the lever 28 is a ratchet 32 having a lug 33 extending into a vertically elongated slot 34 in the upright 12, whereby the ratchet 32 is held against 80 rotation, but is permitted to slide vertically with relation to said upright. A spring 35 secured to the lever 28 normally yieldingly holds the pawl 31 in engagement with the ratchet 32.

In the practical use of my improved circle swing the parts are assembled in the positions hereinbefore described and as shown in the drawings, whereupon a child sitting in one of the seats 23 may pull on the handle or lever 28, thereby swinging the seats around the support 12. The handle 28 will swing readily with the seats so that the child cannot be hurt.

One of the important features of my invention lies in the fact that by loosening the screw 15 and raising the seats and again fastening the screw 15, the height of the seats 23 with relation to the ground may be readily and easily adjusted for children of 95 different sizes.

Attention is called to the extreme simplicity of my improved swing, and the cheapness with which it may be constructed.

Some changes may be made in the construc- 110

tion and arrangement of the parts, and it is my intention to cover by this application and the patent to be issued thereon, any such modifications of structure or the use of mechanical equivalents as may be included within the scope of my claim.

I claim as my invention:

A circle swing comprising an upright support, a plurality of seats mounted for rotation on said support, means for adjustably supporting said seats at different heights on

said support, said upright having a vertically elongated slot, a ratchet on said upright, having a lug projecting into said slot, a handle rotatably mounted on said support, 15 said ratchet being operatively mounted with relation to said handle, and a pawl pivoted to said handle and designed to coact with said ratchet.

Des Moines, Iowa, October 12, 1916.

LUTHER SCOTT.
